METHOD OF MAKING A BUTTON ELEMENT

William C. Broadwell, Forest Hills, N. Y.

Application November 15, 1933, Serial No. 698,139

16 Claims. (Cl. 18—59)

This invention relates to a method of making button elements, such as are adapted to be used, for example, in connection with garment supports of the button-loop type.

- 5 An important object of the invention is to provide an improved method by which button elements, which are simple in construction and reliable in operation, may be economically manufactured.
- 10 Other objects and advantages of the invention will become apparent from the following description, taken in connection with the accompanying drawing, in which—

Fig. 1 is a face view of one form of garment support, with which a button element produced in accordance with the present invention is adapted to be used; Fig. 2 is a transverse sectional view taken on line 2—2 of Fig. 1; Fig. 3 is a rear view of the support shown in Fig. 1, the suspension member for the support being omitted; Fig. 4 is a view similar to Fig. 1 and showing another form of support, with which a button element produced in accordance with the present invention is adapted to be used; Fig. 5 is a transverse sectional view taken on line 5—5 of Fig. 4; Fig. 6 is a rear view of the clasp shown in Fig. 4, the suspension member for the support being omitted; Fig. 7 is a transverse sectional view of the button element and its associated retaining strap shown in Figs. 1 to 6; and Fig. 8 is a view showing in section a mold by which the button element of Figs. 1 to 7 may be formed, the button element and its included retaining strap being shown in section on a plane passing centrally and longitudinally through the button element and its included strap.

Referring to the drawing, the numeral 5 indicates a flexible suspension member, such as a garter strap or the like, to which a garment support, with which a button element produced in accordance with the present invention, is adapted to be connected for longitudinal adjustment thereon.

The particular garment support herein shown as adapted for use with a button element produced in accordance with the present invention includes a loop or loop-like member 6, of suitable material such as sheet metal, the inner wall-like edge of the loop opening 7 presenting a pair of inwardly projecting lugs 8 at opposite sides of the loop opening and at points substantially midway of the length of that opening, and further presenting immediately adjacent the lugs 8 a pair of downwardly and inwardly inclined button-engaging walls 10.

Associated with the loop 6 is a button element 11, which may be produced in accordance with the present invention and which includes a retaining strap 12 and a button 14, the strap being adapted for connection at one end thereof to the

loop 6 by means hereinafter more particularly described.

According to the present invention, the button elements 11 may be produced in quantities by the aid of a suitable mold, which includes a pair of mold members 15 and 16, the latter of which is provided with a plurality of mold cavities 17, only one of which is herein shown but each of which has a configuration conforming to the desired surface contour of the button 14 of the finished button elements. Each of the mold cavities 17 is formed by reason of the fact that the mold member 16 is so recessed as to provide therein a pocket 18, which registers with an opening 20, provided in a face plate 21, secured to the lower face of the mold member 16.

In carrying on the method employed in the production of the button elements 11, a strip of suitable fabric 22, such as a non-stretchable "sheeting", is placed on the upper face of the mold member 15, while the members 15 and 16 are separated, whereupon a quantity of rubber compound 24 is applied to that fabric. After applying the rubber compound, a strip of suitable fabric 25, such as a stretchable "stockinet" material, is placed on top of the rubber compound, whereupon the member 16 is moved downwardly, by suitable means, into engagement with the uppermost strip of fabric, with the result that, as the member 16 assumes its position shown in Fig. 8, the rubber compound is forced upwardly into the mold cavities 17 carrying with it portions of the uppermost layer of fabric 25, thus forming the buttons 14, each of which is characterized by the fact that the displaced portion 35 of the fabric 25 assumes such a position, as shown in Figs. 2, 5, 7 and 8, and it serves as a reinforcing element for the button. As the member 16 assumes its position shown in Fig. 8, the rubber compound is not only displaced in the manner described, but it is also caused to enter and fill the spaces between the threads of the fabric so that the fabric and the rubber compound are firmly united into a unitary structure to be subjected to vulcanization within the mold.

Upon completing the molding operation just described, the button elements 11 may be blanked or otherwise removed from the unitary structure, each button element being reinforced with respect to its included strap 12 as well as its included button 14 by reason of the presence of the fabrics 22 and 25.

A pronounced peculiarity of the button element 11, herein disclosed, resides in the fact that as the garment is subjected to tension, incident to the downward pull exerted thereon when worn, the relatively soft marginal flange-like edges of the button are deflected or urged into impinging engagement with the garment, at points where it is confined between such edges.

and the underlying portions of the loop 6, and through the slot 30 from the rear of the grip plate 28, thence over the web bar 32, and through the space afforded between the web bar 32 and the outer edge of the bite plate 37 while holding the tongue 36 so depressed as to afford a substantial clearance between the web bar 32 and the outer edge of the bite plate 37. The support may then be adjusted to any desired position longitudinally of the suspension member 5 preparatory to its being locked in a desired position of adjustment, whereupon pressure is released from the tongue 36, thus allowing the bite plate 37 to intimately engage the suspension member in the vicinity of the web bar 32 and at a point offset to the right thereof when viewed in Fig. 2. The locking of the support on the suspension member 5 may be easily effected by exerting a pull on the suspension member in the direction of the arrow A in Fig. 1 while holding the clasp against movement. By reason of such pull on the suspension member 5, the bite plate 37, normally engaging the suspension member in the vicinity of the web bar 32, will exert a further impinging action on that member and will move with it to a locking position slightly offset with respect to the web bar 32 to the left thereof, when viewed in Fig. 2, where it is frictionally held against undue reverse movement, movement of the bite plate 37 to its offset locking position being permitted due to the flexibility of the tongue 36 and being limited by reason of the fact that the bite plate is adapted to engage the grip plate at points b—b adjacent opposite sides of the tongue 36. To release the support from its locking position on the suspension member 5, it is only necessary to hold the support against movement while exerting a pull on the gripped end of the suspension member in a direction opposite to the direction indicated by the arrow A in Fig. 1. Such a pull will cause the bite plate 37 to move with a snap action to an offset position with respect to the web bar 32 and slightly to the right thereof when viewed in Fig. 2.

Referring to the form of support shown in Figs. 4 to 6, it will be noted that the locking means by which the device is adapted to be adjustably secured to the suspension member 5 includes a grip plate 28, which is formed integral with the loop 6 and is provided at its upper end with a pair of strap-receiving slots 30, 31, between which is disposed a web bar 32 which is slightly offset, as shown most clearly in Fig. 2, so that the plane of its front face is common to the plane of the rear face of the grip plate. As shown most clearly in Fig. 1, the grip plate 28 is provided with a pair of upwardly and outwardly extending slots 34, and is formed with an opening 35, so as to provide a yieldable and more or less resilient tongue 36, to which a bite plate 37 is pivotally connected by a rivet 38, between the outer edge of which plate and the web bar 32 there is afforded a space which is normally slightly less than the thickness of the clasp-supporting member 5. As shown most clearly in Fig. 2, the rivet 38 is utilized as a means for attaching the button element 11 to the tongue 36, between which and the bite plate 37 the end of the retaining strap 12 is anchored.

In attaching the support to the suspension member 5, the end of that member is passed

Referring further to Figs. 4 to 6, it will be noted that the loop 6 is formed with an aperture 40 and is provided with a struck up tongue 41, between the end of which and the adjacent portion of the loop is afforded a slot 42, the width of which, when the tongue is moved into the plane of the loop, is slightly less than the thickness of the retaining strap 12 of the button element 11. By utilizing the tongue 41, the button element 11 may be effectively anchored to the loop 6, and in doing so the supporting strap 12

is passed through the aperture 40 from the rear of the loop, thence upwardly over the tongue 41 and through the slot 42, whereupon the tongue 41 is moved into the plane of the loop where it exerts an impinging action on the strap 12 which is effective to anchor the button element against undue displacement.

It will be understood that various departures may be made with respect to the method herein described without departing from the spirit of the invention or the scope of the following claims.

What is claimed is:

1. A method of making a button element for use in a garment support of the button-loop type by the aid of a pair of mold members one of which is provided with a mold cavity, comprising superimposing a fabric and a layer of rubber compound on one mold member in a contiguous relation to each other and in such relation to said cavity that said fabric and said compound overlie and extend beyond said cavity and subjecting said compound and said fabric to pressure between said mold members by moving one toward the other, whereby a portion of said compound and a portion of said fabric are forced into said cavity as elements of a composite button there formed and whereby other portions of said fabric and said compound outside of said cavity are forced into intimate relation to each other as elements of a composite tab-forming sheet integral with said button and whereby the spaces intermediate the threads of said fabric are filled with said compound and whereby said compound and said fabric are united in a unitary structure, and severing from said unitary structure the button and an attached portion of said tab-forming sheet to obtain a button element wherein the severed portion of said tab-forming sheet constitutes a tab in integral association with the button.
2. A method of making a button element for use in a garment support of the button-loop type by the aid of a pair of mold members one of which is provided with a mold cavity, comprising superimposing a fabric and a layer of rubber compound on one mold member in a contiguous relation to each other and in such relation to said cavity that said fabric and said compound overlie and extend beyond said cavity and subjecting said compound and said fabric to pressure between said mold members by moving one toward the other, whereby a portion of said compound and a portion of said fabric are forced into said cavity as elements of a composite button there formed and whereby other portions of said fabric and said compound outside of said cavity are forced into intimate relation to each other as elements of a composite tab-forming sheet integral with said button and whereby the spaces intermediate the threads of said fabric are filled with said compound and whereby said compound and said fabric are united in a unitary structure, subjecting said unitary structure to vulcanization, and severing from said unitary structure the button and an attached portion of said tab-forming sheet to obtain a button element wherein the severed portion of said tab-forming sheet constitutes a tab in integral association with the button.
3. A method of making a button element for use in a garment support of the button-loop type by the aid of a pair of mold members one of which is provided with a mold cavity, comprising superimposing a fabric on one mold member that it overlies and extends beyond said
5. A method of making a button element by the aid of a pair of mold members one of which is provided with a mold cavity, comprising superimposing a stretchable fabric and a layer of rubber compound on one mold member in a contiguous relation to each other and in such relation to said cavity that said fabric and said compound overlie and extend beyond said cavity, and subjecting said compound and said fabric to pressure between said mold members by moving one toward the other, whereby a portion of said compound and a portion of said fabric are forced into said cavity as elements of a composite button there formed and whereby other portions of said fabric and said compound outside of said cavity are forced into intimate relation to each other as elements of a composite tab-forming sheet integral with said button and whereby the spaces intermediate the threads of said fabric are filled with said compound and whereby said compound and said fabric are united in a unitary structure, subjecting said unitary structure to vulcanization, and severing from said unitary structure the button and an attached portion of said tab-forming sheet to obtain a button element wherein the severed portion of said tab-forming sheet constitutes a tab in integral association with the button.
6. A method of making a button element for use in a garment support of the button-loop type by the aid of a pair of mold members one of which is provided with a mold cavity, comprising superimposing a fabric and a layer of rubber compound on one mold member in a contiguous relation to each other and in such relation to said cavity that said fabric and said compound overlie and extend beyond said cavity, and subjecting said compound and said fabric to pressure between said mold members by moving one toward the other, whereby a portion of said compound and a portion of said fabric are forced into said cavity as elements of a composite button there formed and whereby other portions of said fabric and said compound outside of said cavity are forced into intimate relation to each other as elements of a composite tab-forming sheet integral with said button and whereby the spaces intermediate the threads of said fabric are filled with said compound and whereby said compound and said fabric are united in a unitary structure, subjecting said unitary structure to vulcanization, and severing from said unitary structure the button and an attached portion of said tab-forming sheet to obtain a button element wherein the severed portion of said tab-forming sheet constitutes a tab in integral association with the button.
7. A method of making a button element for use in a garment support of the button-loop type by the aid of a pair of mold members one of which is provided with a mold cavity, comprising superimposing a fabric on one mold member that it overlies and extends beyond said

whereby said compound and said fabric are united in a unitary structure, and severing from said unitary structure the button and an attached portion of said tab-forming sheet to obtain a 5 button element wherein the severed portion of said tab-forming sheet constitutes a tab in integral association with the button.

6. A method of making a button element by the aid of a pair of mold members one of which 10 is provided with a mold cavity, comprising superimposing a stretchable fabric and a layer of rubber compound on one mold member in a contiguous relation to each other and in such relation to said cavity that said fabric and said 15 compound overlie and extend beyond said cavity, subjecting said compound and said fabric to pressure between said mold members by moving one toward the other, whereby a portion of said compound and a portion of said fabric are forced into 20 said cavity as elements of a composite button there formed and whereby other portions of said fabric and said compound outside of said cavity are forced into intimate relation to each other as elements of a composite tab-forming sheet 25 integral with said button and whereby the spaces intermediate the threads of said fabric are filled with said compound and whereby said compound and said fabric are united in a unitary structure, subjecting said unitary structure to vulcanization, 30 and severing from said unitary structure the button and an attached portion of said tab-forming sheet to obtain a button element wherein the severed portion of said tab-forming sheet constitutes a tab in integral association with the 35 button.

7. A method of making a button element by the aid of a pair of mold members one of which is provided with a mold cavity, comprising so 40 superimposing a non-stretchable fabric on one mold member that it overlies and extends beyond said cavity, so superimposing a quantity of rubber compound on said fabric that it overlies and extends beyond said cavity, so superimposing a stretchable fabric on said rubber compound 45 that it overlies and extends beyond said cavity and subjecting said compound and said fabrics to pressure between said mold members by moving one toward the other, whereby a portion of said compound and a portion of said stretchable fabrics 50 are forced into said cavity as elements of a composite button there formed and whereby a portion of each fabric and a portion of said compound are forced into intimate relation to each other outside of said cavity to there form a composite tab-forming sheet integral with said button and whereby the spaces intermediate the threads of said fabrics are filled with said compound and whereby said compound and said fabrics are united in a unitary structure, and 55 severing from said unitary structure the button and an attached portion of said tab-forming sheet to obtain a button element wherein the severed portion of said tab-forming sheet constitutes a tab in integral association with the 60 button.

8. A method of making a button element by the aid of a pair of mold members one of which is provided with a mold cavity, comprising so 65 superimposing a non-stretchable fabric on one mold member that it overlies and extends beyond said cavity, so superimposing a quantity of rubber compound on said fabric that it overlies and extends beyond said cavity, so superimposing a stretchable fabric on said rubber compound 70 that it overlies and extends beyond said cavity,

subjecting said compound and said fabrics to pressure between said mold members by moving one toward the other, whereby a portion of said compound and a portion of said stretchable fabrics are forced into said cavity as elements of a composite button there formed and whereby a portion of each fabric and a portion of said compound are forced into intimate relation to each other outside of said cavity to there form a composite tab-forming sheet integral with said button and whereby the spaces intermediate the threads of said fabrics are filled with said compound and whereby said compound and said fabrics are united in a unitary structure, subjecting said unitary structure to vulcanization, 15 and severing from said unitary structure the button and an attached portion of said tab-forming sheet to obtain a button element wherein the severed portion of said tab-forming sheet constitutes a tab in integral association with the 20 button.

9. A method of making a button element by the aid of a pair of mold members one of which is provided with a mold cavity, comprising superimposing a non-stretchable fabric and a layer of 25 rubber compound on one mold member in a contiguous relation to each other and in such relation to said cavity that said fabric and said compound overlie and extend beyond said cavity, and subjecting said compound and said fabric to pressure between said mold members by moving one toward the other, whereby a portion of said compound is forced into said cavity to there form a button and whereby the spaces intermediate the threads of said fabric are filled with said compound and whereby said compound and said fabric are united in a unitary structure, and severing from said unitary structure the button and a portion of said overlying fabric and a portion of said overlying compound to obtain a button element wherein the severed portions of said fabric and said compound constitute a tab in integral association with the 35 button.

10. A method of making a button element by the aid of a pair of mold members one of which is provided with a mold cavity, comprising superimposing a non-stretchable fabric and a layer of 40 rubber compound on one mold member in a contiguous relation to each other and in such relation to said cavity that said fabric and said compound overlie and extend beyond said cavity, subjecting said compound and said fabric to pressure between said mold members by moving one toward the other, whereby a portion of said compound is forced into said cavity to there form 45 a button and whereby the spaces intermediate the threads of said fabric are filled with said compound and whereby said compound and said fabric are united in a unitary structure, subjecting said unitary structure to vulcanization, and severing from said unitary structure the button and a portion of said overlying fabric and a portion of said overlying compound to obtain a button element wherein the severed portions of said fabric and said compound constitute a tab in 50 integral association with the button.

11. A method of making a button element by the aid of a pair of mold members one of which is provided with a mold cavity, comprising superimposing on one mold member a fabric and a 55 quantity of rubber compound and a second fabric in a contiguous relation to each other and in such relation to said cavity that the fabrics and the compound overlie and extend beyond said cavity, and subjecting said compound and said fabrics to 60

pressure between said mold members by moving one toward the other, whereby a portion of said compound and a portion of one of said fabrics are forced into said cavity as elements of a composite 5 button there formed and whereby a portion of each fabric and a portion of said compound are forced into intimate relation to each other outside of said cavity to there form a composite tab-forming sheet integral with said button and 10 whereby the spaces intermediate the threads of said fabrics are filled with said compound and whereby said compound and said fabrics are united in a unitary structure, and severing from said unitary structure the button and an attached 15 portion of said tab-forming sheet to obtain a button element wherein the severed portion of said tab-forming sheet constitutes a tab in integral association with the button.

12. A method of making a button element by 20 the aid of a pair of mold members one of which is provided with a mold cavity, comprising superimposing on one mold member a fabric and a quantity of rubber compound and a second fabric in a contiguous relation to each other and in such 25 relation to said cavity that the fabrics and the compound overlie and extend beyond said cavity, subjecting said compound and said fabrics to pressure between said mold members by moving one toward the other, whereby a portion of said 30 compound and a portion of one of said fabrics are forced into said cavity as elements of a composite button there formed and whereby a portion of each fabric and a portion of said compound are forced into intimate relation to each other outside 35 of said cavity to there form a composite tab-forming sheet integral with said button and whereby the spaces intermediate the threads of said fabrics are filled with said compound and whereby said compound and said fabrics are united in a unitary structure, subjecting said unitary structure to vulcanization, and severing from said unitary structure the button and an attached portion of said tab-forming sheet to obtain a button element 40 wherein the severed portion of said tab-forming sheet constitutes a tab in integral association with the button.

13. A method of making a button element by 45 the aid of a pair of mold members one of which is provided with a mold cavity, comprising superimposing on one mold member a non-stretchable fabric and a quantity of rubber compound and a stretchable fabric in a contiguous relation to each other and in such relation to said cavity that the fabrics and the compound overlie and 50 extend beyond said cavity, and subjecting said compound and said fabrics to the pressure between said mold members by moving one toward the other whereby a portion of said compound and a portion of said stretchable fabric are forced into said cavity as elements of a composite button there formed and whereby a portion of each fabric and a portion of said compound are forced into intimate relation to each other outside of 55 said cavity to there form a composite tab-forming sheet integral with said button and whereby the spaces intermediate the threads of said fabrics are filled with said compound and whereby said compound and said fabrics are united in a unitary structure, subjecting said unitary structure to vulcanization, and severing from said 60 unitary structure the button and an attached portion of said tab-forming sheet to obtain a button element wherein the severed portion of said tab-forming sheet constitutes a tab in integral association with the button.

14. A method of making a button element by the aid of a pair of mold members one of which is provided with a mold cavity, comprising superimposing on one mold member a non-stretchable fabric and a quantity of rubber compound and a stretchable fabric in a contiguous relation to each other, subjecting said compound and said fabrics to the pressure between said molds by moving one toward the other whereby a portion of said compound and a portion of said stretchable fabric are forced into said cavity as elements of a composite button there formed and whereby a portion of each fabric and a portion of said compound are forced into intimate relation to each other outside of said cavity to there form a composite tab-forming sheet integral with said button and whereby the spaces intermediate the threads of said fabrics are filled with said compound and whereby said compound and said fabrics are united in a unitary structure, subjecting said unitary structure to vulcanization, and severing from said unitary structure the button and an attached portion of said tab-forming sheet to obtain a button element wherein the severed portion of said tab-forming sheet constitutes a tab in integral association with the button.

15. A method of making a button element by the aid of a pair of mold members one of which is provided with a mold cavity, comprising so superimposing a non-stretchable fabric on one 30 mold member that it overlies and extends beyond said cavity, so superimposing a quantity of rubber compound on said fabric that it overlies and extends beyond said cavity, and subjecting said compound and said fabric to pressure between 35 said mold members by moving one toward the other, whereby a portion of said compound is forced into said cavity to there form a button and whereby the spaces intermediate the threads of said fabric are filled with said compound and 40 whereby said compound and said fabric are united in a unitary structure, and severing from said unitary structure the button and a portion of said overlying fabric and a portion of said overlying compound to obtain a button element wherein the 45 severed portions of said fabric and said compound constitute a tab in integral association with the button.

16. A method of making a button element by the aid of a pair of mold members one of which is provided with a mold cavity, comprising so superimposing a non-stretchable fabric on one mold member that it overlies and extends beyond said cavity, so superimposing a quantity of rubber compound on said fabric that it overlies and extends beyond said cavity, and subjecting said compound and said fabric to pressure between 50 said mold members by moving one toward the other, whereby a portion of said compound is forced into said cavity to there form a button and 55 whereby the spaces intermediate the threads of said fabric are filled with said compound and whereby said compound and said fabric are united in a unitary structure, subjecting said unitary structure to vulcanization, and severing from said 60 unitary structure the button and a portion of said overlying fabric and a portion of said overlying compound to obtain a button element wherein the 65 severed portions of said fabric and said compound constitute a tab in integral association with the 70 button.
